UNITED STATES PATENT OFFICE.

SOLOMON KAMEL GAR, OF PATERSON, NEW JERSEY, ASSIGNOR OF ONE-HALF TO
TOBIAS GREENBERG, OF PATERSON, NEW JERSEY.

STOP-MOTION FOR LOOMS.

1,358,214.

Specification of Letters Patent.

Patented Nov. 9, 1920.

Application filed July 1, 1920. Serial No. 393,237.

To all whom it may concern:

Be it known that I, SOLOMON KAMEL GAR, a citizen of the Republic of Poland, residing at Paterson, in the county of Passaic and 5 State of New Jersey, have invented certain new and useful Improvements in Stop-Motions for Looms, of which the following is a specification.

This invention relates to means for stopping a loom of the box-loom type whenever it inadvertently happens that when a shuttle is in position to be shot across the lay or batten another shuttle is in a box which is alined with the lay, so that a smash would 10 occur if the first shuttle were thrown. The object of the invention is to provide a means of this kind which, while efficient and reliable in operation, shall be simple in construction.

20 In the accompanying drawing,

Figure 1 is a front elevation of the batten structure and the parts of my mechanism which are carried thereby;

Fig. 2 is a plan view showing the batten structure, the breast-beam-including part of the loom frame, and my mechanism;

Figs. 3 and 4 are sectional views on the line 3—3, Fig. 2, showing the parts in the positions they occupy before and after the 30 knocking-off action has occurred; and

Fig. 5 is a sectional view on the line 5—5, Fig. 1.

On the loom-frame *a* is the breast-beam *b*, and suitably arranged to reciprocate toward 35 and from the breast-beam is the batten *c*. *d* indicates a single shuttle box at one end of the batten and *e* a vertical series of shuttle boxes moved up and down at the other end of the batten by any suitable means, not 40 shown. Each shuttle box has a binder *e'* which is movable outwardly by the shuttle, in the usual way, when the same enters the box, such binder being in the present instance a part of my means for stopping the 45 loom and so preventing a smash.

In the frame *a* under the breast-beam is journaled the usual knock-off shaft *f*, the same being provided in the present instance with a collar *g* having a downwardly projecting toe *h*.

A plate *i* is secured to the front of the batten opposite the collar *g* and is formed with a vertical dove-tailed groove *j*. This plate has a forwardly projecting hook-shaped arm *k* in which is fulcrumed the

dagger *l* arranged when the batten moves forward to miss said toe or impinge against the same, according as the dagger stands depressed or elevated. In the groove *j* slides a block *m* which is normally impelled downwardly by gravity (assisted by a spring *n*, if desired). This block *m* has a depending stem *m'* which is pivotally connected to the rear end of the dagger. The block has a cross cut or horizontal groove *o* in its front 60 face.

The block is normally held elevated, thus holding the free end of the dagger depressed, so as to miss the toe *h* of the collar *g*, by the protector rods *p* alined with each other and journaled horizontally in brackets *q* attached to the batten. The inner end of each rod is bent to form a crank *r* which is engaged in the groove *o* and is normally held therein by a spring *t* which is coiled about the rod and is secured at one end to a collar *u*, adjustably secured on the rod, and at the other end to the adjoining bracket *q*. The outer end of the protector rod which adjoins the series of shuttle boxes *e* has an arm *v* which bears against the shuttle binders *e'* of those boxes; the outer end of the other protector rod is formed as a crank *w* and bears upon the forwardly projecting arm of a lever *x*, fulcrumed in the batten and having an upwardly projecting arm to bear against the binder *e'* for the adjoining or single shuttle box *d*.

The operation is as follows: So long as there is only one shuttle in the box *d* and one 90 of the boxes *e* alined with the batten the means to actuate the knock-off shaft (such means including the slide *m*) will be held in the position shown in Fig. 1 or Fig. 3, i. e., so that the point of the dagger will be 95 depressed and consequently miss the toe *h*; this is because, although the shuttle present has caused the corresponding protector rod to rock to the position shown in Fig. 4, since there is no shuttle in the box alined with and at the other end of the batten, the other protector rod remains in locking engagement with the groove *o* of the slide, holding it elevated. But if both boxes alined with the batten contain shuttles, then both protector 100 rods will have been rocked and so caused to release the slide, so that it falls and allows the dagger to assume the position shown in Fig. 4, and then on the next beating-up movement of the batten the dagger will 110

strike the toe *h* and so rock the knock-off shaft.

The dagger-impact face of toe *h* is preferably arranged at such an angle that on the dagger impinging thereagainst and rocking the knock-off shaft to the dotted line position, said face will assume an inclined position (dotted lines, Fig. 4) and so serve as a cam thereupon to depress the point of the dagger and cause the latter to elevate the slide, so that upon removal of one of the two shuttles the corresponding protector rod will again interlock with the slide and hold it and the dagger in the idle position.

Having thus fully described my invention, what I claim as new and desire to secure by Letters Patent is:—

1. In combination, with the loom frame, knock-off means movable therein, and a batten structure movable in said frame and having shuttle-boxes at the ends thereof, means to actuate the knock-off means including a slide movable in the batten structure from a position to clear to a position to engage the knock-off means and normally im-

peled to the latter position, and separate means, disconnectively coupled with the slide, to hold the second means in the former position, each of said separate means being respectively actuatable by a boxed shuttle to release the slide. 30

2. In combination, with the loom frame, knock-off means movable therein, and a batten structure movable in said frame and having shuttle-boxes at the ends thereof, means 35 to actuate the knock-off means including a slide movable vertically in the batten structure from a position to clear to a position to engage the knock-off means and normally impelled to the latter position, and separate means to hold the second means in the former position, each of said separate means including a protector rod journaled in the batten and actuatable by one of two boxed shuttles aligned with the batten and having a crank 40 movable into and out of interlocking engagement with the slide. 45

In testimony whereof I affix my signature.

SOLOMON KAMELGAR.
